UNITED STATES PATENT OFFICE

LEWEN R. NELSON, OF PEORIA, ILLINOIS

SPRINKLER

Application filed May 17, 1929. Serial No. 363,799.

The present invention relates to sprinklers.

Among the objects of the invention is to provide a novel sprinkler device of the rotary type, such as are used for sprinkling or watering 5 golf greens, lawn surfaces, gardens and the like.

The invention comprehends a novel device adapted to water a maximum area and to constantly operate without attention. In 10 the rotary type of sprinkler, if a far throw of the water be desired, the sprinkler must rotate slowly, so that as much of the energy as possible in the water stream may be utilized in projecting the stream and as little 15 as possible used in causing the rotation of the sprinkler. When a sprinkler rotates slowly, the rotative parts generally bind or stick or have such friction that the sprinkler ceases to rotate. To maintain continuous rotation 20 it is necessary to prevent such binding or sticking and one way to effect such rotation is to vibrate the sprinkler to destroy or prevent any tendency of the rotative parts binding or sticking.

25 An object of the invention is to provide a novel sprinkler of rotative type with means to vibrate the sprinkler and preferably with means for varying or adjusting the vibrating action as also the rate of rotation. By the 30 present invention, slow rates of rotation and great throw of water are possible.

In an illustrative embodiment of the invention, the water is forced through a conduit at the end of which is rotatably mounted 35 a sprinkler head carrying a duct of relatively large diameter and running preferably radially to an upwardly directed discharge nozzle adapted to project the main portion of the water stream moving through 40 the conduit, to a maximum distance, the head also carrying another preferably radially disposed and smaller diameter duct leading to a rotation producing nozzle having a spray orifice or the like and capable of being adjustably set to effect any desired component 45 moment of force about the axis of rotation of the head, the orifice being also adjustable for projecting the water over an inner area of the area swept by the discharge nozzle previously 50 mentioned.

Another object of the invention is to provide an adjustable means, such as an adjustable connection for the nozzle of the larger duct, whereby the stream may be projected therefrom at any desired angle to the axis of 55 the duct, and thus assist in the rotating of the sprinkler.

The invention comprehends means, such as a valve in the duct leading to the spray nozzle, for regulating the vibration of the 60 head and its rotative movement.

Another feature of the invention is to provide a nozzle of novel construction, the elements of which are so designed and arranged that water passing through the nozzle will 65 set up a vibration which is imparted to the head to constantly jar it and prevent it from binding or becoming temporarily fixed in any one position. This vibrating action is of importance because of the fact that the greatest 70 economy in time and water consumed is procured when the head is positively and slowly rotated about its axis. Ordinarily, without the vibration, the head would bind or become fixed due to the friction of the rotating element at these slower speeds of rotation. 75

Another object of the invention is to provide a nozzle of novel construction having a discharge opening at the side and adapted to project a fan shaped spray of water to 80 one side of the nozzle.

In the specific embodiment selected to illustrate the invention, a nozzle is provided with a longitudinal chamber in which is positioned a diaphragm having an orifice therein, and at one side of the nozzle is a discharge opening communicating with the enlarged longitudinal chamber with another of less diameter. The discharge opening is adjacent to the end of the chamber of less diameter and is cut into the side of the chamber angularly and substantially semi-circular to project a fan shaped spray of water to one side of the nozzle. The water passing through the orifice means and into the chambers and through the nozzle causes a vibration of the nozzle and likewise of the head to prevent the same from binding or becoming fixed when it rotates slowly. 90

The orifice in the vibrator or spray nozzle 100

is so arranged that the water issues therefrom in the form of a spray. By providing means, such as a valve in the passage leading to this nozzle, or an apertured or orificed plate or disc, or both, the pressure of water in the nozzle outlet chamber is so affected, as by reducing the same, that the water spray issues in large or coarse drops. The air resistance to the mass of the drops is less for 10 large drops than for smaller drops or particles of the same total mass. The stream with the larger drops will be cast farther and will not be carried away by the wind, as would be the case if the drops were reduced to a fine spray or mist. In this way the valve, or apertured disc, or both, regulate the quality of spray, as also the vibration of the sprinkler, the vibration increasing and decreasing with the opening and closing of the 15 valve or the using of a larger or smaller orifice in the disc, or both, respectively.

Also, when partly closing the valve, or reducing the disc orifice, or both, in the smaller limb, the flow and pressure of water is increased in the larger limb with the advantage 20 of the stream from the latter covering a greater distance and a greater area.

Another advantage gained by reduction of flow effected at the valve, or orificed disc, or both, is that the friction and wear between the relatively moving parts, is greatly reduced and the device has a longer life, as also being more reliable and dependable for correct operation.

35 The invention also comprehends the providing of a nozzle to cause vibrations in the head of a sprinkler either with or without the orifice means.

40 A further object of the invention is to provide a novel nozzle device comprising a fitting which is adapted to be connected to a water supply conduit and which is adapted to adjustably hold a nozzle.

45 Another feature of the invention is to provide a novel nozzle device comprising a fitting in which the nozzle may be adjustably connected to the nozzle fitting.

The invention further comprehends the 50 providing of a valve means in the nozzle fitting, the valve means being constructed so as to seat with the walls of an inlet conduit fitting into the nozzle fitting, and which is in communication with the water supply conduit.

55 A further object of the invention is to provide novel means for filtering or straining the water passing through the duct to the spray nozzle, this filtering means being so related to the duct of the discharge nozzle that the water passing from the water supply conduit will self-scour or wipe and clean the filter or strainer.

60 Other objects, advantages, features and capabilities are comprehended by the inven-

tion, as will later appear and as are inherently possessed thereby.

Referring to the drawing:

Fig. 1 is a view in side elevation of an embodiment selected to illustrate the invention, 70 with parts broken away to show the filtering or straining means.

Fig. 2 is a top plan view of the embodiment illustrating the invention.

Fig. 3 is a vertical cross sectional view 75 taken in the plane represented by the line 3-3 of Fig. 2.

Fig. 4 is a vertical cross-sectional view 80 taken in the plane represented by the line 4-4 of Fig. 2.

Fig. 5 is a top plan view showing the areas watered by the respective nozzles on the rotating sprinkler head.

Referring now more in particular to the drawing, the embodiment selected to illustrate the invention comprises a support 1 which may be either stationary or movable from place to place, and supporting a water supply pipe 2 rotatably mounted on the support 1. The upper end of the supply pipe 2 85 discharges into a suitable distributing member formed by an elbow 3, having a threaded engagement with said pipe and also threadedly engaged with a laterally extending pipe or conduit 4. The upper end of the duct 4 90 is provided with a socket 5 adapted to receive the ball end of a discharge nozzle 6, for directing a stream of water upwardly and in a substantially radial direction and over a large area as designated as A in Fig. 5 of the 100 drawing. The nozzle may have any suitable control means 6a. It may be angularly adjusted by the turning of the ball in the socket 5, to any desired angle. In this way the rotative action of the sprinkler may be 105 assisted.

The elbow 3 has a lateral boss or nipple 7 threaded to receive the threaded end of a radially extending pipe or auxiliary conduit 8. A perforated plate 9 substantially thimble-shaped and having flanges 10 adapted to engage shoulders 11 in the bore of the projection 7 and held in place by the abutting end of the conduit 8, is provided to filter or strain the water passing into the conduit 8. This plate 110 or strainer 9 projects out into the bore of the elbow 3, and is so positioned that the flow of water in and through the elbow together with the eddying and whirlpool action of the water adjacent to the elbow bend, will provide means for scouring and self-flushing and preventing accumulation and retention of any sediment or other material on the face of the strainer.

115 A fitting 12 which may be T-shaped has a limb 13 threaded to the outer end of conduit 8 and an oppositely located limb 14 provided with threaded bores 15 and 15a adapted to receive a threaded enlargement 16 on a valve 120 stem 17 having a knurled cap or button 18 125

exterior of the fitting 12. The stem 17 is provided at its inner end with a beveled or valve surface 19 adapted to seat with a beveled surface or valve seat in the inlet 20 in the limb 5 13 and forming an inlet from the conduit 8 into a chamber 21 in the body portion of the fitting 12. The stem 17 is positioned by a gland 22 acting to compress packing ring 23 for preventing leakage about the stem 17. A 10 washer 24 seats against a shoulder 25 between bores 15 and 15a and sustains the packing 23. The quantity of water passing through the conduit 8 and into the chamber 21 in the fitting 12 may be regulated conveniently by 15 turning and varying the engagement of the end 19 of the stem 17 and the valve seat at inlet 20.

The upper limb or discharge branch 12a of the fitting 12 is threaded to receive a hollow stem member 27 having a reduced diameter portion 27a to form an annular chamber 28 between such portion and the walls of a hub member 29 which is rotatably and slidably mounted on the stem 27. The chamber 25 28 communicates with the chamber 21 through openings 30 in the walls of the hollow stem member, and in turn communicates with a bore or chamber 31 of a discharge nozzle 32. At the upper end of the hollow stem 27 are ears 33 for screwing the threaded end of the stem into the threaded bore of the fitting 12. A gasket or washer 34 is provided between hub 29 and shoulder 35 to prevent leakage therebetween. A similar gasket or 35 washer 36 is provided between hub 29 and limb 12a to prevent leakage around the joint between the hub 29 and fitting 12.

The end of the discharge nozzle 32 is threaded to receive a coupling-nut 37 which 40 is provided with an annular shoulder 38 adapted to engage an annular shoulder 39 of a nozzle tip 40, to hold the nozzle tip in an operative position. A circular diaphragm or disc 41 having a throttling orifice 42 may be 45 interposed between the ends of nozzle tip 40 and member 32 and held abutting the same when the coupling nut is tightened.

The nozzle tip 40 has a chamber 43 adjacent to the diaphragm 41 and a chamber 44 50 of less diameter, at the end of the nozzle and beyond the chamber 43. An opening or port 45 is provided in the side of the nozzle and is cut substantially semi-circular and angularly with the longitudinal axis of the nozzle 55 tip 40. The nozzle tip 40 is adapted to throw or project water out through the opening 45 in a spray-like body to water or sprinkle an area designated B in Fig. 5 of the drawing.

The vibration of the head is present with 60 or without the disc 41. In this connection, it will be noted that the discharge port 45 of the nozzle tip 40 is provided with inclined walls 45a, the surfaces of which tend to check the flow of water, and thereby set up a certain amount of vibration. However, the

character of the bore or chamber 44 has a great deal to do with the quality of vibration imparted to the device. Said bore or chamber, as shown in the drawing, is provided with a cone shaped section 44a which extends toward the end of the nozzle tip beyond the slot 45. This arrangement provides a small chamber below the outer edge of the slot, and together with the reduced bore thereof, seems to set up a backwash or disturbance of the stream which materially increases the amount of vibration. 70 75

The hub member 29 is adjustable about the stem 27 and likewise the nozzle 40 may be adjusted by the coupling nut 37. These adjustable features of the nozzle device, together with the valve adjustment permit a very close control of the amount of water passing through the nozzles, the vibrating action of the head, the speed of rotation, and amount of area watered and likewise the quantity of water to either area A or B or both. 80 85

While I have herein described and upon the drawing illustrated particular embodiments of the invention, it is to be understood that the latter is not limited thereto, but comprehends other details, arrangements of parts, features and constructions, without departing from the spirit thereof. 90 95

Having thus disclosed my invention, I claim:

1. A sprinkler device, comprising a head rotatable on a supply pipe, said head having an upward and laterally extending main conduit, an auxiliary conduit extending laterally from said main conduit and communicating therewith, nozzles at the ends of said conduits, means projecting into the main conduit and associated with said auxiliary conduit 100 for filtering the water passing from said supply pipe to said auxiliary conduit, said means being wiped and cleaned by the flow of water through said main conduit. 105

2. In a sprinkler, a nozzle device comprising a fitting having inlet and discharge branches, a hub portion mounted for rotative adjustment upon said discharge branch, and means engaging the interior of said discharge branch for locking said hub portion in any 110 desired rotative adjustment with respect to the fitting, and a radially disposed discharge conduit extending from said hub member. 115

3. In a sprinkler, a nozzle device comprising a fitting having inlet and discharge branches, a hub member mounted for rotative adjustment upon said discharge branch, means for engaging the interior of the discharge branch for locking said hub member in any desired rotative adjustment with respect to the fitting, a radially disposed discharge conduit extending from said hub member at an angle to the horizontal, and a valve controlling the passage between the two branches of said fitting. 120 125 130

4. In a sprinkler, a nozzle device comprising a fitting having inlet and discharge branches, a hub member mounted for rotative adjustment upon said discharge branch, means engaging the interior of said discharge branch for locking said hub portion in any desired rotative adjustment with respect to the fitting, a radially disposed discharge conduit extending from said hub member and means providing a discharge orifice for said conduit so arranged as to project a spray-like body of water in an angular direction with respect to the axis of said discharge conduit.
5. In a sprinkler, a nozzle device comprising a fitting having inlet and discharge branches, a hub portion mounted for rotative adjustment upon said discharge branch, means engaging the interior of said discharge branch for locking said hub member in any desired rotative adjustment with respect to the fitting, a radially disposed discharge conduit projecting from said hub member, and a nozzle tip adjustably mounted on said conduit and having a discharge orifice positioned to project fluid to one side thereof.
6. In a sprinkler, a nozzle device comprising a fitting having inlet and outlet branches, a hollow stem projecting from said discharge branch, a hub member rotatively adjustable on said stem, a discharge conduit projecting from said hub member, and means providing a port for said conduit, so positioned and arranged as to project a spray-like body of water in an angular direction with respect to the axis of said conduit, said stem being adjustable relative to said fitting so as to hold said hub in adjusted positions.
7. In a sprinkler, a nozzle device comprising a fitting having inlet and outlet branches, a hollow stem projecting from said discharge branch, a hub member rotatably adjustable on said stem, and a discharge conduit leading from said hub member and having a discharge port, said stem having means for conducting fluid from said fitting to the interior of said hub member and also having a shoulder for clamping said hub member between it and said fitting.
8. In a sprinkler, a nozzle device comprising a fitting having inlet and discharge branches, a hub member mounted for rotative adjustment upon said discharge branch, means engaging the interior of said discharge branch for locking said hub member in any desired rotative adjustment with respect to said fitting, a radially disposed discharge conduit leading from said hub member, a partition extended across said conduit and provided with an orifice, and a nozzle tip adjustably mounted on the end of said conduit said tip being closed at its outer end and having a discharge orifice in its side.
9. A sprinkler device comprising a rotatable head provided with a chamber, main and auxiliary conduits extending from said head

and radially with respect to said head, filtering means projecting from the inlet end of said auxiliary conduit and extended transversely into said chamber, so as to be cleansed by the flow of water to the other conduit.

10. A sprinkler comprising a rotatably mounted head provided with radially disposed conduits, a discharge nozzle on the outer end of one of said conduits, said nozzle having means operable during discharge of water therefrom for applying rotative power to said head but normally insufficient to overcome the resistance to rotation due to binding of the head, and means carried by the other conduit for vibrating said head so as to prevent binding thereof and free the same for rotation, said means including a hub member communicating with said last mentioned conduit and a discharge conduit projecting radially and downwardly therefrom, a nozzle tip closing the outer end of said discharge conduit and having an inclined discharge slot in its side disposed at an angle with respect to the axis of said discharge conduit and also having a vibration chamber therein extended below the further edge of said slot.

11. A sprinkler comprising a rotatably mounted head provided with radially disposed conduits, a discharge nozzle on the outer end of one of said conduits, said nozzle having means operable during discharge of water therefrom for applying rotative power to said head but normally insufficient to overcome the resistance to rotation due to binding of the head, and means carried by the other conduit for vibrating said head so as to prevent binding thereof and free the same for rotation, said means including a hub member adjustably mounted on said last mentioned conduit and provided with a discharge conduit, a nozzle tip detachably connected with and closing the outer end of said discharge conduit, said tip having an inclined discharge slot in its side disposed at an angle with respect to the axis of said discharge conduit, and also having a vibration chamber of less diameter than the bore of said discharge conduit and extended beyond the outer wall of said slot.

12. A sprinkler comprising a rotatably mounted head provided with radially disposed conduits, a discharge nozzle on the outer end of one of said conduits, said nozzle having means operable during discharge of water therefrom for applying rotative power to said head but normally insufficient to overcome the resistance to rotation due to binding of the head, and means carried by the other conduit for vibrating said head so as to prevent binding thereof and free the same for rotation, said means including a discharge conduit, a nozzle tip removably connected with and closing the outer end of said discharge conduit, said tip having an

inclined discharge slot in its side disposed at an angle with respect to the axis of said discharge conduit and also having a vibration chamber therein of less diameter than the bore of said discharge conduit and extending beyond the outer wall of said slot, and throttling means interposed between said discharge conduit and said nozzle tip.

13. A sprinkler comprising a rotatably mounted head provided with radially disposed conduits, a discharge nozzle on the outer end of one of said conduits, said nozzle having means operable during discharge of water therefrom for applying rotative power to said head but normally insufficient to overcome the resistance to rotation due to binding of the head, means carried by the other conduit for vibrating said head so as to prevent binding thereof and free the same for rotation, said means including a discharge conduit, means connected with and closing the outer end of the discharge conduit providing an inclined discharge slot for said discharge conduit disposed at an angle to the axis of the conduit, said means further providing a vibration chamber beyond the further wall of said slot and having a conical end wall, and means for throttling the flow of fluid to said discharge slot, said throttling means including means for controlling the volume of water passing to the vibration chamber, so as to govern the degree of vibration.

14. A sprinkler comprising a rotatably mounted head provided with radially disposed conduits, a discharge nozzle on the outer end of one of said conduits, said nozzle having means operable during discharge of water therefrom for applying rotative power to said head but normally insufficient to overcome the resistance to rotation due to binding of the head, means carried by the other conduit for vibrating said head so as to prevent binding thereof and free the same for rotation, said means including a valve casing, a discharge nozzle communicating with said valve casing and having a discharge orifice positioned to project fluid to one side thereof, means in said casing controlling the volume of liquid flowing to said nozzle, means providing a restricted orifice in said passage between the valve and the orifice, and means providing a vibration chamber positioned beyond the discharge orifice.

55 In witness whereof, I hereunto subscribe my name to this specification.

LEWEN R. NELSON.
